UNITED STATES PATENT OFFICE.

JAMES S. MCKEEBY, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS.

DESIGN FOR A JEWELRY BOX OR SIMILAR ARTICLE.

Application filed February 23, 1928. Serial No. 25,547. Term of patent 7 years.

To all whom it may concern:

Be it known that I, JAMES S. MCKEEBY, a citizen of the United States of America, residing at Framingham, in the county of Middlesex and Commonwealth of Massachusetts, have invented a new, original, and ornamental Design for Jewelry Box or Similar Article, of which the following is a specification, reference being had to the accompanying drawing, forming a part thereof.

In said drawing,

Fig. 1 is a front elevation of a jewelry box, showing my new design; and Fig. 2 is a side elevation thereof.

The invention resides in the configuration shown and in the provision of a jewelry pad or holder arranged between the side walls of the display box.

I claim:

The ornamental design for a jewelry box or similar article, substantially as shown and described.

Signed by me at Framingham, in the county of Middlesex and Commonwealth of Massachusetts, this twentieth day of February, 1928.

JAMES S. MCKEEBY.
